DISCHARGE TUBE AMPLIFIER

Alexander Nyman, Weehawken, N. J., assignor, by
mesne assignments, to Radio Corporation of
America, New York, N. Y., a corporation of
Delaware

Original application February 25, 1931, Serial No.
518,098. Divided and this application Decem-
ber 31, 1934, Serial No. 759,824

5 Claims. (Cl. 250—20)

This application is a division of and contains matter from United States application Serial No. 518,098 filed February 25, 1931, issued as Patent No. 1,986,597 on January 1, 1935.

5 In the parent application, I have described a new type of cascade amplifying system comprising substantially a plurality of amplifying valves connected in series with a suitable coupling element and an operating current source as distinguished from the usual parallel connection of amplifying valves heretofore used in the art. The advantages of an amplifier of this type residing, among others, primarily in the use of a single coupling element for an increased number of cascade stages, increased selectivity, have been set forth, and the function and operation of such series type amplifier systems explained in detail in the parent application.

10 The present application relates to improvements and novel combinations of series amplifying systems of the type under discussion having for its main object to increase the efficiency and reliability of operation of systems of this type.

15 A more specific object of this invention is to provide means for using a series amplifier for high frequency in combination with a detector for demodulation and means for further amplification of the demodulated signal energy.

20 Another object of the invention is to provide means for using the same series amplifier for amplifying different frequencies or ranges of frequencies, such as first, for amplification of incoming radio frequency energy, and furthermore for detection or demodulation of the receiving 25 signals energy and for amplifying the received demodulated or low frequency signals.

25 A further object of the invention is to provide means in connection with a series amplifier for one frequency for detecting and further amplifying the detected signals in the series amplifier and for segregating the currents of different frequencies or frequency ranges through their respective channels to substantially prevent mutual interference between separate frequencies or frequency ranges of the amplifier.

30 Still another object of the invention is to utilize a series amplifier designed for amplifying one frequency or a definite range of frequencies in combination with a detector and an amplifier for currents at another frequency and utilizing a portion of said series amplifier as a coupling element for further amplification.

35 Another object of the invention is to utilize a series amplifier for superheterodyne reception wherein the incoming high frequency signals are

transformed into a different intermediate frequency, amplified at intermediate frequency and then demodulated to supply the audio output signals.

40 A further object of this invention is to utilize a series amplifier for reception of radio frequency signals according to the heterodyne method including the necessary beating oscillator as an integral part of the series amplifier.

45 A further object of the invention is to incorporate in a series amplifier or amplifying system according to the invention, means for securing automatic volume control action.

50 The invention has further objects in view which will appear hereinafter as the detailed description proceeds taken with reference to the accompanying drawing wherein:

55 Figure 1 illustrates a super-heterodyne receiving circuit embodying a series amplifier according to the invention and a separate local oscillator.

60 Figure 2 shows a modification of a superheterodyne circuit embodying two series amplifiers according to the invention, one operating at intermediate frequency and another at audio frequency, and an oscillator incorporated in the first series amplifier.

65 Figure 3 illustrates a further modified superheterodyne circuit wherein the oscillator is included in the radio frequency series amplifier chain and the intermediate frequency supplied by a separate series oscillator.

70 Similar reference characters identify similar elements throughout the different views of the drawing.

75 Referring to Figure 1, I have shown an arrangement of a series amplifier utilizing a so-called super-heterodyne connection. The general operation of a super-heterodyne includes the conversion of the received signals into another frequency known as intermediate frequency, and amplification at this intermediate frequency for further demodulation into audio frequency.

80 In Figure 1, the antenna 34 with a coupling coil 33 and a ground connection 35 is shown. The coil 33 is coupled to a tuning circuit comprising coil 31 and a variable condenser 32. The tuned circuit forms a part of the input circuit of the first tube of a series amplifier, consisting of tubes T1, T2, T3, and T4. The cathode 3 of the tube T1 is connected through a coupling coil 100 and a bias resistor R2 with a bypass condenser 57, to the negative supply lead 2. The coil 100 is coupled to another coil 101, which may be the output coil of an oscillator 102, the connections 55

of which are not shown, but which may be of any standard type of oscillator, including a variable condenser 103. This variable condenser may be arranged for a common control 104 with the 5 variable condenser 32, these condensers being designed, as is usual, for super-heterodyne sets, to have values of capacities at all settings, such as to produce a definite difference of frequencies in the tuned circuit 31—32 and the oscillator 102. 10 Thus, heterodyne beats are introduced in the grid 4 of tube T1 and amplified through series amplifiers T2, T3, and T4.

I have shown the grid 15 of tube T2 connected to a grid condenser 105 and a grid leak 106, the 15 purpose of which is to demodulate the heterodyne currents of the tube T1 impressed on the cathode of tube T2, so as to leave substantially only intermediate frequency on the subsequent tubes T2, T3, and T4. I have shown, moreover, a bypass 20 condenser 107 from the plate of tube T2 and a radio frequency choke coil 108 between the plate of tube T2 and the cathode of tube T3. The object of the bypass condenser 107 and the choke 25 108 is to localize the radio frequency oscillations to the tubes T1 and T2 and permit intermediate frequency variations only to pass on to tubes T3 and T4. I have also shown a coupling element 30 in series with the plate 109 of tube T4, consisting of a tuned circuit consisting of inductance 110 and a condenser 111 arranged to be within the frequency range of the intermediate frequency. The coil 110 is coupled through the coil 112 to another tuned circuit comprising the coil 112 and condenser 113 and the combination of the two 35 above tuned circuits, forms the necessary coupling element with a high impedance over the intermediate frequency range necessary for successful transmission of the modulated signals; that is, it may be a range of frequency of 10 kilocycles, say, around an intermediate frequency of 100 kilocycles, or whatever other intermediate frequency is chosen.

The design of such a filter is well known in the 40 art and any alternative construction may be utilized. I have shown the output of the intermediate frequency coupling element connected from the coil 112 to the grid 114 of the second detector D, which demodulates the intermediate frequency into audio frequency. To assist demodulation, a grid condenser 115 and a grid leak 45 116 may be used, but this is not always necessary. The other lead from coil 112 is shown connected between a grid bias resistor 117 in series with the cathode 118 of tube D and a volume control tube 119 which, as is shown, may 50 act as a rectifier for changes in the plate current of tube D.

The grid 120 and plate 121 of the tube 119 are 55 shown connected together and bypassed to the cathode 122 of the same tube, by means of resistor 123 and condenser 124. The combination of tube 119, resistor 123, and condenser 124, is designed for a large time constant so as to give the 60 variations of voltage, only due to sustained excessive signals. Thus, an excessive signal coming in at detector D would result in an appreciable diminution of the average plate current of this tube and a consequent reduction of the potential across the rectifier tube 119 and the resistor 123. A tap 65 125 on resistor 123 applies the reduced potential to the control grid 15 of tube T2, which acts as a first detector and, by lowering its potential, will reduce the effectiveness of this tube as a detector and as an amplifier, so that the signal amplified 70 75

by tubes T3 and T4, and detected by tube D is also reduced.

A condenser 126 is shown bypassed from the tap 125 to the negative lead 2. The detector tube D may be coupled to a power amplifier tube P by 5 means of direct connection from its plate 127 to the grid 9 of the power tube, and a plate coupling resistance R5 may be supplied. The power tube may be connected in any desired manner, for instance, as shown in Figure 5 of my above mentioned patent, and is not specifically illustrated in this diagram. Although this diagram shows ordinary three-electrode tubes used, it is quite evident that screen grid tubes could be similarly utilized and that such screen grid tubes could also 10 be connected to the potentiometer R3, which is used for the series amplifier, in exactly the same manner as has been shown in said patent.

Referring to Figure 2, an alternative arrangement is shown in which the series amplifier consisting of tubes T1, T2, T3, and T4 may have for tube T1, a tube with a space charge grid 130, in addition to the control grid 4. In this case, I can utilize this space charge grid to produce oscillations in the tube T1, by connecting an oscillator 20 circuit comprising variable condenser 103 and a coil 101 in the circuit of the grid 130, a coil 100 coupled with 101, and a bypass condenser 131 in the circuit of the plate 5 of tube T1. Thus, while the input circuit 31—32 applies a potential at incoming frequency to the control grid 4, the space charge grid 130 at the same time applies an oscillation of a frequency determined by the oscillatory circuit of condenser 103 and coil 101.

I have shown a grid bias resistor R2 with a bypass condenser 57 in the input circuit and a high resistance bypass 132 in parallel with condenser 131. This combination will act effectively as a demodulating circuit, so that the tubes T2, T3 and T4 will receive substantially only intermediate frequency oscillations and will amplify such oscillations, as a series amplifier, due to the presence of the filter circuit consisting in this case, of three tuned circuits S3, S4 and S5, in series with the plate 109 of tube T4 and on account of the connections from the control grids of tubes T2, T3 and T4 to the potentiometer R3.

The output from the filters S3, S4, and S5 extends through a condenser 7 to a second detector tube D, which converts the intermediate frequency signals to audio frequency and has a grid leak resistance 133 and the following volume control arrangement. A rectifier tube 119, similar to Figure 1 is connected in series to the cathode 118 of tube D, and a tap point 125 on a bypass resistor 50 123 is used to supply the grid bias to the grid 114 of the tube D, via the grid leak 133. A bypass condenser 126 is supplied on the volume control and also a bypass condenser 124 in parallel with the rectifier tube 119. This condenser is arranged 55 with the resistor 123 and the impedance of tube 119 to have the necessary long time constant. The tube D may have an intermediate frequency bypass condenser 134 from plate 127 to cathode 118 and a choke coil 135, suitable to block off the 60 intermediate frequency.

As a result, only variations of audio frequency 65 will reach a further amplifier tube T5 in series amplifier connection with the tube D. The grid 136 of tube T5 may be supplied with a constant 70 potential from the common potentiometer R3. The output of tube T5 and, if necessary, of a further amplifier tube (not shown) connected and in series with it, is obtained from a coupling transformer 70, which may lead further into a 75

power amplifier stage (not shown). It will be seen that in this case the volume control arrangement is applied to the second detector, while in Figure 1 the volume control was applied to the first detector. Either of these arrangements may have advantages, depending on the particular design of the amplifier. Thus, the connection of Figure 1 gives a more effective volume control over a wider range of amplitudes, while Figure 2, with a simpler oscillator arrangement, gives also a simpler volume control arrangement.

I have shown in Figure 3 another alternative arrangement in which the series amplifier T₁, T₂ and T₃ uses the tube T₁, as a radio frequency input tube, and the tube T₂ as an oscillator. The tube T₂ has its grid 15 connected to a tuned circuit comprising variable condenser 103 and a coil 101. A tickler coil 100 is connected to the anode 6' of tube T₂. A back coupling condenser 131 is used to connect the tickler coil back to the cathode 16 of tube T₂. A grid bias resistor 136 may be supplied if necessary for the tube T₂ used as oscillator.

The variable condenser 103 is shown to have a common control 104 with the variable condenser 32 of the input circuit 31-32, and also with the coupling circuits S₁ and S₂, which are arranged in exactly the same manner as the circuits 31-32 and 103-101, to give the frequency response to the two heterodyning frequencies in the series amplifier T₁, T₂ and T₃. Thus, the heterodyning frequencies are permitted to be freely amplified up to the anode 6 of tube T₃ and at the same time, certain demodulation to intermediate frequency will take place in this series amplifier.

This demodulation will impress the potential at intermediate frequency only to a further series filter of intermediate frequency, which may be exactly similar to that of Figure 1 and consisting of a primary 110 with condenser 111 and a secondary 112 with a condenser 113. I have shown the output of the secondary 112 applied to a further intermediate frequency series amplifier consisting of tubes T₄, T₅ and T₆, with series coupling circuits S₃ and S₄, which are arranged to have a high impedance over the modulated intermediate frequency range, that is, the same range for which the first intermediate frequency filter of coil 110 with condenser 111 and coil 112 with condenser 113, were designed.

The arrangement for producing the intermediate frequency by beating the incoming frequency current with the locally produced oscillations as shown in Figures 2 and 3 has the advantage that the mixing of the two frequencies is carried out purely electronically in that the two discharge streams produced by the tubes T₁ and T₂ (see Figure 3) connected in series and one of the streams (T₁) is controlled by the incoming frequency currents while the other stream (T₂) is caused to vary or oscillate at a locally generated frequency differing from the incoming frequency by the amount of the desired intermediate or beat frequency, the latter being received by the tuned circuit 110, 111 for further amplification as described. In this manner, as is understood, the coupling between the incoming frequency currents and the locally generated frequency currents is purely electronic; that is, through the electron stream only, whereby the mixing effect is a direct one in that one stream affects the other in a multiplicative manner, resulting in a great efficiency of the frequency conversion and lack of distortion as compared to the systems previously known such as shown in Figure 1 wherein

the two currents, that is, the local frequency and the incoming frequency currents, are superimposed in the same grid circuit making it necessary to operate the tube as a rectifier with the attendant disadvantages of distortion and others to secure a true intermediate frequency current.

Thus, the intermediate frequency signals will be freely amplified through the second series amplifier and simultaneously demodulated, resulting in audio frequency changes of impedance, which may be directly impressed upon a series audio frequency transformer 70 with an intermediate frequency by-pass condenser 137. The output coil 71 of transformer 70 may be applied to further audio frequency amplifier of any suitable design and supplied, for instance, with a volume control terminal 138 and the supply terminals 139 and 140, connected respectively to positive lead 1 and negative lead 2.

The volume control terminal 138 may be used, for instance, for controlling the potential of the screen grids of tubes T₄, T₅ and T₆, by means of potentiometer R_{3'} in an arrangement similar to that of Figure 1. I have supplied a choke coil 139', in order to prevent any changes of radio frequency that may exist in resistor R_{3'} from reaching the volume control terminal 138. As it is necessary to use tube T₄ partly as a detector at audio frequency, I have supplied, moreover, a grid bias resistor 140 in the cathode circuit of this tube, together with a by-pass condenser 141 and a plate by-pass 142, which, however, may be omitted, and also a screen grid by-pass condenser 143 which may also be omitted, without greatly affecting the operation of this device. A choke coil 144 serves furthermore, to prevent any changes at radio frequency from reaching the intermediate frequency amplifiers T₄, T₅ and T₆.

While I have illustrated a number of modifications of the uses of series amplifier in superheterodyne circuits, I do not wish to be limited to the particular circuits or theoretical consideration outlined in the specification, except as defined in the appended claims.

I claim:

1. An amplifying system comprising a plurality of discharge valves each having a cathode, anode and at least one control electrode; a first coupling impedance; a source of high potential; said valves, said impedance and said source being in series, with the anode of one valve connected to the cathode of the succeeding valve; means for applying impulses of a predetermined frequency range to one of said valves; said impedance having a high impedance to frequencies of said frequency range; means for converting said impulses into impulses of a different frequency range; at least one further valve and means for impressing said converted impulses of the different frequency range upon said further valve; and a second impedance means in series with said last mentioned valve and having a high impedance to variations of current of said different frequency range.

2. In an electrical system comprising a plurality of discharge valves each having a cathode, an anode and at least one control electrode; a plurality of impedance means each designed to present high impedance to a different frequency range; a source of high potential supply; said valves, said impedance means and said source being in series with the anode of one valve connected to the cathode of a succeeding valve; means for applying input potential variations of

- a certain frequency range to one valve of said series; and frequency changing means forming a part of said series for converting potential variations of said first frequency range to potential variations of another frequency range.
3. In an amplifying system comprising a plurality of discharge valves each having a cathode, anode and at least one control electrode; a source of high potential, said valves and said source being in series, with the anode of one valve connected to the cathode of the succeeding valve, said valves being divided into a plurality of groups; a plurality of coupling impedances in series with said valves having different frequency characteristics whereby each of said groups amplifies currents at a different frequency range from the adjacent group, circuit means cooperating with a valve adjacent successive groups for converting the impulses amplified by the preceding group into impulses of the next following frequency range; and means for by-passing impulses of a pre-determined frequency range from portions of said amplifying series transmitting impulses of a different frequency range.
4. An electrical system comprising a plurality of discharge valves each having a cathode, anode, and at least one control electrode; a source of high potential; said source and said valves being in series, with the anode of one valve connected to the cathode of the succeeding valve; means whereby one of the valves within said series acts as a frequency converter to change the input frequency range applied to the first of said valve series into a different frequency range; at least two impedance means connected in series with said valves and said high potential source and 5 designed each to present high impedance to said first and second frequency ranges, respectively, whereby part of said series operates at more than one frequency; and by-passing means around the other part of said series effective for currents 10 having a frequency transmitted by the remaining portion of said series.
5. An electrical system comprising a plurality of discharge valves each having a cathode, anode, and at least one grid electrode; a source of high 15 potential supply; a first impedance; means for applying high frequency modulated input signals to one of said valves to produce amplified potential variations across said impedance; circuit means connected to another of said valves which is adapted to act as a detector oscillator beating with the high frequency signals to produce intermediate frequency signals; a second impedance connected to another of said valves which is adapted to produce amplified potential variations 20 at intermediate frequency across said second impedance; and means for by-passing currents of said intermediate frequency around said first valve operating at high frequency.
